UNITED STATES PATENT OFFICE.

LOUIS STEINBERGER, OF BROOKLYN, NEW YORK.

DESIGN FOR A LOUD SPEAKER.

Application filed November 26, 1924. Serial No. 11,498. Term of patent 3½ years.

To all whom it may concern:

Be it known that I, LOUIS STEINBERGER, a citizen of the United States, and a resident of the borough of Brooklyn, county of Kings, city and State of New York, have invented a new, original, and ornamental Design for a Loud Speaker, of which the following is a specification.

The design is illustrated in the accompanying drawing in which—

Figure 1 is a perspective front view of the loud speaker.

Fig. 2 is a top plan view of the loud speaker with the scalloped edge omitted therefrom.

I claim:

The ornamental design for a loud speaker, as shown.

In witness whereof I have hereunto set my hand at the city, county and State of New York, this 21st day of November, 1924.

LOUIS STEINBERGER.
